PRESSING TOOLS PARTICULARLY FOR THE MANUFACTURE OF LARGE-AREA PRESSINGS

Kurt Lang, Wolfgang Barthel, Wilhelm Ladewig, Fritz Hans, and Werner Reichelt, Zwickau, Erich Klauss, Mosel, near Zwickau, and Alfred Schädlich, Zwickau, Germany

Application November 16, 1955, Serial No. 547,231

9 Claims. (Cl. 18—35)

The present invention relates to press molding machines, and more particularly to pressing tools forming part thereof which are capable of being heated and cooled for the manufacture of predominantly large-area pressings consisting preferably of synthetic materials.

It is known in the art to provide thick-walled steel tools for the pressing of large-area pressings. In these tools pressures of 250—400 kilograms per square centimeter are applied, the material flowing only at such high pressures. However, thick-walled tools cannot be applied to pressings which are to be cooled after the pressing operation because the required cooling after each pressing takes too much time and thus is uneconomical.

It is an object of the present invention to provide a pressing tool adapted to press large-area parts to be cooled after the pressing operation.

It is another object of the present invention to equalize any differences in the accumulation of the material in the body to be pressed.

According to one embodiment of the present invention large-area pressings to be cooled after the pressing operation are manufactured by means of pressing tools in which a heat insulating layer is arranged on the base member of the lower portion of the tool, and a shell-shaped mold provided with heating channels is arranged on the heat insulating layer whereas the upper part of the tool is provided with a rubber pad traversed preferably by heating tubes and being attached to the counter-member or press ram by means of an interposed heat insulating layer.

The rubber pad is intended to equalize any differences in the accumulation of materials of the preliminary body to be pressed, and any changes of the pressing gap caused by heat expansion of the material. Without this rubber pad it is impossible to press the preliminary material in a perfectly uniform manner at low pressures amounting approximately to 40 kilograms per square centimeter. This holds particularly for parts to be subjected to a high degree of deformation.

The base member for the lower portion of the tool as well as for the rubber pad consists preferably of cast iron, compact timber, steel with magnesite, the material known under the trade name Igurit, concrete, or similar materials.

Other objects and advantages of the present invention will become apparent from the following detailed description thereof in connection with the accompanying drawings showing, by way of example, some embodiments of a pressing tool according to the present invention. In the drawings

Fig. 1 is a sectional elevation of part of a pressing tool for parts capable of an easy deformation.

Figs. 2—4 illustrate several embodiments of fastening means for a rubber pad forming part of the pressing tool shown in Fig. 1.

Fig. 5 is a sectional elevation on an enlarged scale of part of the pressing mold shown in Fig. 1.

Fig. 6 is a sectional elevation of a swage for making

2

a part of a pressing tool according to the present invention.

Fig. 7 is a sectional part elevation on an enlarged scale of another embodiment of the present invention.

Fig. 8 is a sectional elevation of a further embodiment of the present invention.

Fig. 9 is a sectional elevation on an enlarged scale of part of the embodiment shown in Fig. 8.

Fig. 10 is a part section of still another embodiment of the present invention.

Fig. 11 is a sectional elevation of a still further embodiment of the present invention.

Fig. 12 is a sectional elevation on an enlarged scale along the line A—B shown in Fig. 13.

Fig. 13 is a plan view of some parts shown in Fig. 12, and

Fig. 14 is a sectional elevation of part of a pressing tool incorporating the parts shown in Figs. 12 and 13.

Referring now to the drawings in detail and first to Fig. 1, a base member 3 is provided with a bowl shaped recess 1. An insulating layer 6 consisting of a material being a poor conductor of heat is arranged in the recess 1, the layer 6 being rigidly connected to the base member 3 by suitable means 7. The heat insulating layer 6 is subdivided by separating fillets or bars 10 into square panels having dimensions of about 200 millimeters x 200 millimeters. A thin foil 19 consisting preferably of rolled lead is arranged on the insulating layer 6. A shell-shaped mold 14 preferably consisting of neatly machined steel is provided on the lower side thereof with a plurality of heating channels 2.

As shown in Fig. 5, the heating channels 2 are covered by cover sheets 4 consisting preferably of metal which are separated from each other by filling strips or bands 5 in order to obtain a smooth contact and sliding surface. The metal sheets 4 and filling strips 5 are welded by welding joints 5a to the shell-shaped mold 14, the upper side of which corresponds to the shape of the article (not shown) to be pressed from a synthetic material by the pressing tool.

The prepressed material (not shown) is pressed into the shell-shaped mold 14 by means of a rubber pad 11 consisting of a synthetic rubber of medium hardness, or a similar heat resistant rubber mixture. The rubber pad 11 is surrounded by a strong frame 12 and vulcanized with the rim portion thereof to the latter. However, if desired the rubber pad 11 may be fastened to the frame 12 by screw bolts 16 cooperating with countermembers 17 such as nuts and sleeves 18 arranged on the screw bolts 16 between the frame 12 and the countermember 17. This kind of connection facilitates and accelerates the exchange of the rubber pad 11.

A system of heating pipes 13 is arranged in the rubber pad 11 near the upper side thereof. An insulating layer 9 consisting of a material being a poor conductor of heat is arranged above the rubber pad 11. A counter-member or pressing ram 8 is arranged above the insulating layer 9 which is subdivided by Z-shaped brackets 15 fastened by screw bolts such as 15a to the pressing ram 8. The Z-shaped parts 15 extend through the insulating layer 9 and form the cover of the recesses 13a provided in the rubber pad 11 accommodating the heating pipes 13. The Z-shaped parts 15 carry the rubber pad 11 by means of parts such as stirrups 33 and anchoring members 32 vulcanized into the rubber pad 11. The insulating layer 9 is subdivided into small fields by partitions 10 similar to the insulating fillets or bars 10 arranged in the heat insulating layer 6. The mold 14 is connected with the rim thereof by a connecting member 20a arranged at the rim portion of the heat insulating layer 6, to a centering

member 20 connected to the base member 3 by screws such as 20b.

The operation of this device is as follows:

If an article is to be pressed by the pressing tool described hereinabove the pressing ram 8, the insulating layer 9 and the rubber pad 11 are lifted from the position shown in Fig. 1 by driving means (not shown). A heating fluid such as steam is admitted to the heating channels 2 and pipes 13 so as to heat thoroughly the shell-shaped mold 14 and the rubber pad 11. After the same are sufficiently heated, the material to be pressed, preferably a synthetic material, is inserted between the shell-shaped mold 14 and the rubber pad 11. Then the movable parts of the pressing tool including the pressing ram 8, the insulating layer 9, and the rubber pad 11 are lowered so that the material to be pressed is caught between the shell-shaped mold 14 and the rubber pad 11, the deformation of the material being promoted and facilitated by the heat transferred to the mold 14 and the pad 11 by the heating fluid circulating in the channels 2 and the pipes 13. After the material to be pressed, preferably a synthetic material has been shaped, the heating fluid circulating in the channels 2 and the pipes 13 is replaced by a cooling agent which circulates through the channels 2 and the pipes 13 so that the pressed article is rapidly cooled and may be removed from the pressing tool after lifting the movable parts 8, 9, and 11 thereof. The pressed part is then removed and the pressing tool is ready for a further operation.

The shell-shaped mold 14 consists preferably of steel and is so thin, for instance 12-18 millimeters thick, that it may be manufactured from a flat steel plate which in the flat condition thereof is machined and finished and provided with the heating channels 2. After performing these steps the plate is pressed in warm condition in a swage shown in cross-section in Fig. 6 and consisting of a lower part 63 and an upper part 64. In many cases the base member 3 shown in Fig. 1 may be formed so as to be usable as part of a swage for imparting to the mold 14 the final shape thereof.

The foil 19 consisting preferably of rolled lead facilitates any displacements of the mold 14 against the heat insulating layer 6.

Referring now to the modified embodiment shown in Fig. 7, a shell-shaped mold 714 is attached on the lower side thereof by a welding joint 70 to a relatively short threaded sleeve 71 into which the end 72 of a holding screw 30 projects through the base member 73 and the heat insulating layer 76.

Referring now to Figs. 8 and 9 of the drawings showing a mold for manufacturing highly deformed molded pieces, the mold 814 is shaped as a part manufactured from a steel plate having a uniform thickness t . The mold 814 is secured to an auxiliary member 831 having a smooth and continuously curved lower side 809 enabling the auxiliary member 831 to yield to, and if desired, to slide on, the supporting or base member (not shown) under the influence of heat, particularly during the heating up stage. If the auxiliary member 831 consists of heat insulating material the heat insulating layer 6 shown in Fig. 1 may be omitted. The heat insulating member 831 is preferably subdivided into square fields by fillets or bars 810. On the lower side of the mold 814 are provided heating channels 811 which are limited by chutes 821 welded by welding material such as 812 to the lower side of the smooth mold 814. If desired, the mold 814 may be held in position by screws such as 816 arranged in a boring of the auxiliary member 831 and engaging a countermember such as nuts 815 provided on the lower side of the mold 814.

Referring now to Fig. 10 of the drawings the mold 1014 is formed as a cast piece provided with heating channels 1002 arranged in the mold 1014.

Referring now to Fig. 11 of the drawings a pressing tool is shown for pressing parts having unilaterally raised left and right hand edges. The base member 1103 is provided in the center thereof with an expansion joint 1124. The left part 1114 and the right part 1114a of the mold are provided, respectively, with portions 1116 and 1116a having a reduced thickness and being connected by a holding ledge 1123 secured in position by means of a screw bolt 1125 extending through the expansion joint 1124. A metal sheet 1122 covers the holding ledge 1123, the sheet 1122 joining to each other the parts 1114 and 1114a of the mold 1114. A heat insulating layer 1106 is subdivided by separating fillets or bars 1110 into square panels similar to those shown in the embodiment shown in Fig. 1.

Referring now to Figs. 12-14 of the drawings, a mold is shown intended for the manufacture of large-dimensioned molded pieces having upright edges which either extend over the whole circumference of the molded piece or are provided on two opposite parts thereof. As shown in Figs. 12 and 14 the mold consists of two parts 1214 and 1214a similar to those shown in Fig. 11. The expansion joint 1224 arranged between the two halves 1214 and 1214a of the mold is covered by a metal strip 1229 welded to one of the halves, for instance 1214 by a welding seam 1230. Between the free edge of the metal strip 1229 and the other half, say 1214a, of the mold a groove 1226 is formed which has a width changeable according to the heat expansion of the metal strip 1229, the synthetic material (not shown) during the pressing step filling the groove 1226. On the lower side of the halves 1214 and 1214a of the mold are provided fingers 1227, 1228 covering the lower end of the expansion joint 1224 and welded, respectively, by welding joints 1225, 1232 to the parts of the mold. As will be seen from Fig. 13 the fingers 1227, 1228 are welded alternately to the parts 1214 and 1214a of the mold, the finger 1228 being welded by the welding seam 1232 to the part 1214. The part 1214 of the mold is separated by a gap 1234 from a centering member 1204 held by screws 1205 on the base member 1203 and holding the insulating layer 1206 in position, the insulating layer 1206 supporting the part 1214 of the mold. The right part 1214a is provided with a centering member 1236 held in position on the base member 1203 by a screw 1238.

Although the present invention has been described hereinabove with reference to the embodiments of a pressing tool shown in the drawings it should be understood that the present invention is in no way limited to the embodiments shown in the drawings and that various modifications thereof, changes, and substitutions of equivalents will be apparent to those skilled in the art, the embodiments of a pressing tool described hereinabove being only to be understood as examples of the present invention.

We claim:

1. A molding tool adapted to press-mold synthetic material of relatively large area comprising, a rigid base; a heat insulating layer anchored to said base; and a mold liner of relatively hard, heat conducting material nested on said insulating layer, said insulating layer being interposed between said base and said liner and thereby substantially insulates the former from the latter, said liner having an exposed surface adapted to receive material to be molded and also having at least one channel for carrying fluid for varying the temperature of said liner, said liner being slidably supported and loosely arranged on said insulating layer for relative displacement therebetween to accommodate relative thermal expansion and contraction, and a rolled lead foil interposed between said insulating layer and said liner to facilitate relative displacement between said liner and said insulating layer.

2. A molding tool adapted to press-mold synthetic material of relatively large area comprising, a rigid base; a

heat insulating layer anchored to said base; and a mold liner of relatively hard, heat conducting material nested on said insulating layer, said insulating layer being interposed between said base and said liner and thereby substantially insulates the former from the latter, said liner having an exposed surface adapted to receive material to be molded and also having at least one channel for carrying fluid for varying the temperature of said liner, said liner being slideably supported and loosely arranged on said insulating layer for relative displacement therebetween to accommodate relative thermal expansion and contraction, the rim of said liner is slideably supported with respect to said heat insulating layer.

3. A molding tool adapted to press-mold synthetic material of relatively large area comprising, a rigid base; a heat insulating layer anchored to said base; and a mold liner of relatively hard, heat conducting material nested on said insulating layer, said insulating layer being interposed between said base and said liner and thereby substantially insulates the former from the latter, said liner having an exposed surface adapted to receive material to be molded and also having at least one channel for carrying fluid for varying the temperature of said liner, said liner being slideably supported and loosely arranged on said insulating layer for relative displacement therebetween to accommodate relative thermal expansion and contraction, said liner has a plurality of channels open towards said insulating layer, further comprising, cover sheet means arranged on the open sides of said channels, and filler strips arranged between said cover sheet means, said filler strips and said cover sheet means forming a smooth contact surface slideably engaging said insulating layer.

4. A molding tool as claimed in claim 2 further comprising, stops secured to said base member, said stops being positioned to limit the relative displacement between said liner and said insulating layer.

5. A molding tool adapted to press-mold synthetic material of relatively large area comprising, a rigid base; a heat insulating layer anchored to said base; and a mold liner of relatively hard, heat conducting material nested on said insulating layer, said insulating layer being interposed between said base and said liner and thereby substantially insulates the former from the latter, said liner having an exposed surface adapted to receive material to be molded and also having at least one channel for carrying fluid for varying the temperature of said liner, said liner being slideably supported and loosely arranged on said insulating layer for relative displacement therebetween to accommodate relative thermal expansion and contraction, said liner comprises to two adjacent sections defining an expansion joint therebetween.

6. A molding tool as claimed in claim 5, and a metal strip welded to the rim of one of said first and second liner sections and extending to overlap the expansion joint between said first and second liner sections.

7. A molding tool as claimed in claim 5, and finger-shaped members securing the edges of said first and second liner sections in position along the expansion joint.

8. A molding tool as claimed in claim 7, said finger-shaped members being secured alternately to the lower sides of said first and second liner sections so as to engage the edges thereof along the expansion joint.

9. A molding tool adapted to press-mold synthetic material of relatively large area comprising, a rigid base, a heat insulating layer anchored to said base, and a mold liner of relatively hard, heat conducting material nested on said insulating layer, said insulating layer being interposed between said base and said liner and thereby substantially insulates the former from the latter, said liner having an exposed surface adapted to receive material to be molded and also having at least one channel for carrying fluid for varying the temperature of said liner, said liner being slideably supported and loosely arranged on said insulating layer for relative displacement therebetween to accommodate relative thermal expansion and contraction, a countermember, a heat insulating layer anchored to said countermember, and a die member of elastic material, said material being uniformly solid throughout its body, said die member being vulcanized to said last-mentioned insulating layer and having a deformable surface turned toward the exposed surface of said liner, said last-mentioned insulating layer being interposed between said countermember and said die member, said deformable surface being urged into contact with the material to be molded upon said countermember and base member being forced together under pressure, and said die member being provided with channels for carrying a fluid for changing the temperature of said die member, and a frame enclosing said die member, screw means supported in said frame, nut means arranged for cooperation with said screw means, said nut means consisting of a vulcanizable material embedded in said die member and hollow distance pieces arranged between said frame and said nut means, said screw means extending through said hollow distance pieces.
